(57) **CLAIM**

The ornamental design for a toilet brush, as shown and described.

DESCRIPTION

FIG. 1 is a left perspective view of the toilet brush showing our new design;

FIG. 2 is a front view thereof;

FIG. 3 is a back view thereof

FIG. 4 is a left-side view thereof;

FIG. 5 is a right-side view thereof;

FIG. 6 is a top view thereof; and,

FIG. 7 is a bottom view thereof.

The broken lines shown are included for the purpose of illustrating portions of the toilet brush that form no part of the claim.

1 Claim, 7 Drawing Sheets
